DENTAL ARTICULATOR AND ATTACHMENTS THEREFOR

Anthony J. De Pietro, Springfield, Pa., assignor to Medical Electronics and Research Corporation, Camden, N.J., a corporation of New Jersey

Filed Jan. 9, 1963, Ser. No. 250,985

2 Claims. (Cl. 32—32)

This invention relates generally to apparatus for use in dental prosthesis, and particularly to apparatus for use in fabricating artificial dentures.

This application is a continuation-in-part of my co-pending application Serial No. 62,190 now abandoned, filed October 12, 1960.

In the fabrication of artificial dentures, it becomes necessary to secure various members to the upper section or bow member of a dental articulator, for example, a clutch tray or a denture model. The general practice is to use an auxiliary mounting table essentially including a horizontally extending base, an upright post at the front of the base and an adjustable stand at the rear of the base. A suitably adjusted dental face bow is mounted upon the post and arranged so that it extends rearwardly in overlying vertically spaced relation to the base. The stand is provided with a head extending horizontally across the rear of the table and with a pair of elements threaded respectively into the opposite end portions of the head and adjustable for varying the length thereof.

The stand is adjusted as required to bring the longitudinally extending axis of the head into coincidence with the axis extending between the opposed points of the condyle pins of the face bow and to bring the remote ends of the threaded elements into contact respectively with the opposed points of the condyle pins. Then the upper section of the articulator is mounted with its rear end resting upon the head of the stand and its front end resting upon the face bow. The upper clutch tray, which is attached to the face bow, is now suitably loaded with stone and secured to the upper section of the articulator. This use of the stand in accordance with general practice has not proved to be entirely satisfactory because the threaded elements merely abut the points of the opposed condyle pins without positively interengaging therewith, and the weight of the stone normally causes the longitudinally extending axis of the head and the axis extending between the opposed points of the condyle pins to shift relative to each other, in consequence of which there occurs an appreciable error in mounting the clutch tray upon the upper bow member.

In the fabrication of artificial dentures, clutch trays formed over denture models are secured respectively to the upper and lower bow members of the articulator. Extending forwardly from the rims of these trays are clutch bars which are positioned by using a conventional jig. While the jig positively positions the clutch bars relative to one another so that it is possible for the incisal pin to pass freely therebetween, it does not positively position them relative to the incisal pin. The operator must depend upon his own good judgment for this, and a slight error in orienting the jig very often makes it impossible to close the incisal pin on the incisal guide due to interference by a clutch bar. Thus much time, labor and material may be lost because it is impossible to correctly position and secure the lower clutch tray to the lower bow member of the articulator unless the incisal pin can close on the incisal guide. The necessity for arranging the clutch bars so that they cannot interfere with the closing of the incisal pin on the incisal guide is important not only when the fabrication of artificial dentures involves the use of stone checks, but also when it involves the use of pantographs.

2

An object of the present invention is to provide improved means for relating the upper section of a dental articulator to the dental face bow before the operation of attaching to said upper articulator section an upper clutch tray or a model of the upper denture.

Another object is to provide such means which positively interengages with the opposed ends of the condyle pins of the face bow thereby to maintain throughout the operation aforesaid coincidence of the axis extending between the opposed points of the face bow condyle pins and the hinge axis of the upper bow member of the articulator.

Another object is to provide such means which positively interengages with the opposed ends of the condyle pins of the face bow in the manner aforesaid irrespective of whether the condyle pins are of the type provided with points or of the type provided with depressions or sockets in the opposed ends thereof.

Another object is to provide means which facilitate supporting the face bow for receiving and operatively mounting the upper section of the articulator.

Another object is to provide means which facilitate positively positioning clutch bars to effectively avoid any interference with the incisal pin and guide of the articulator.

Another object is to provide a pair of posts interchangeably mountable upon the fore end of the lower section of a dental articulator, one of said posts being operatively for supporting the face bow in overlying spaced relation to said lower articulator section and the other being operable for positively positioning clutch bars to effectively avoid any interference with the incisal pin and guide of the articulator.

Other objects of the invention will become apparent when the following description is read with reference to the accompanying drawings, in which:

FIGURE 1 is a side elevation of a dental articulator;
FIGURE 2 is a fragmentary enlarged one-half section on line 2—2 of FIGURE 1;

FIGURE 3 is an enlarged one-half section through the rear of the upper bow member of the articulator showing the hinge part arranged for receiving a face bow condyle pin;

FIGURE 4 is a perspective view showing a face bow mounted upon the lower bow member of the articulator and mounting the upper bow member of the articulator;

FIGURE 5 is a diagrammatic side view of the articulator showing upper and lower clutch trays mounted upon the lower bow member and a pair of denture models attached respectively to the upper and lower bow members and closer respectively upon the clutch trays;

FIGURE 6 is a vertical section on line 6—6 of FIGURE 5;

FIGURE 7 is a diagrammatic side view of the articulator showing the instrument turned upside down, the fore ends of the bow members spaced by the incisal pin and guide and the upper clutch tray secured to the upper bow member;

FIGURE 8 is similar to FIGURE 7, but shows the lower tray secured to the lower bow member;

FIGURE 9 is a front elevation of the instrument as shown in FIGURE 8;

FIGURE 10 is a rear elevation of the face bow mounting post;

FIGURE 11 is a side, and FIGURE 12 is a top, view of the post shown in FIGURE 10;

FIGURE 13 is a front view of the clutch tray mounting post;

FIGURE 14 is a side, and FIGURE 15 is a top, view of the post shown in FIGURE 13;

FIGURE 16 is a front elevation of a modified face bow mounting post;

FIGURES 17 and 18 are opposite side views of the post shown in FIGURE 16;

FIGURE 19 is similar to FIGURE 17, but shows the post mounted upon the lower bow member and in turn mounting the face bow; and

FIGURE 20 is a fragmentary plan view of the structure shown in FIGURE 19.

Referring particularly to FIGURES 1 to 4, an articulator constructed in accordance with the invention comprises a lower bow member including a main body portion 10 terminating at the rear thereof in a pair of laterally spaced upright posts 12. Each post 12 mounts a condylar head or hinge part in the form of a spherical element 14 formed integral with a neck 16 terminating in a disc 18 slidable in a groove 20, which groove is formed in a horizontally extending head 22 on the post 12. Carried by the body 10 are a pair of guide pins 26 and a lock screw 28 adapted for securing to the lower bow member the mounting plate (not shown) for a lower jaw model.

Overlying the lower bow member is an upper bow member including a main body portion 30 terminating at the rear thereof in a pair of wings 32 extending laterally outwardly in opposite directions. Each wing 32 mounts a hinge part in the form of an assembly, generally designated 34. Carried by the body 30 are a pair of guide pins 36 and a lock screw 38 adapted for securing to the upper bow member the mounting plate (not shown) for an upper jaw model.

Each assembly 34 comprises a condylar guide in the form of a major part of a flat circular disc 40 disposed in an upright position with its principal axis passing horizontally through the center of the underlying spherical element 14 and having an arcuate outer edge 42 and a pair of straight angularly related edges 44 and 46, as shown. The guide 40 is suitably recessed to afford an abutment 48 and a curvilinear condyle surface 50 having an arcuate posterior portion 52 and an arcuate anterior portion 54. Each abutment 48 and surface 50 is adapted to slidably engage the associated spherical element 14.

Each assembly 34 includes a condylar guide mount in the form of a bifurcated member 56 having a base portion 58 joining a pair of arms 60 and 62. These arms depend from the base in laterally spaced relation to one another and conjointly with the base embrace a marginal area of the guide 40. Press-fitted into the arm 60 is a pin 64 slidably projected into the center of the disc 40. Press-fitted into the arm 62 is a pin 66 projecting into an arcuate groove 68 in the disc 40. Referring particularly to FIGURE 3, extending lengthwise of the base 58 of the condylar guide mount, is an index mark 69.

Extending from the base 58 is a stem in the form of a tubular element 70. Fitted over the stem 70 is a washer 72 provided with a diametrically extending tongue 74 and an axially extending index mark 75. Immediately above the washer 72 is a second washer 76 provided with a diametrically extending tongue 78. Threaded onto the stem 70 is a nut 80 counterbored, as at 82, for accommodating a coil spring 84 extending about the stem 70. Threaded into the stem 70 is a screw 86, the terminal portion of which screw is adapted to engage the guide 40.

As thus far described, the hinge part 34 is essentially the same as a hinge part described in copending application, Serial No. 856,425, filed December 1, 1959, which has since matured into United States Patent No. 3,019,530, dated February 6, 1962, to which reference may be made for the details of construction and operation not disclosed herein. The washers 72 and 76 are disposed respectively in underlying and overlying relation to the wing 32 of the upper face bow with their tongues 74 and 78 slidably fitted in a slot 88. The pin 64 is provided with an abutment in the form of a head 90 axially tapered, as at 92, and provided with an axially extending conical depression 94.

The upper bow member mounts an adjustable incisal

pin 96, and the lower bow member mounts an adjustable incisal guide 98 secured thereto by a screw 99. Both the incisal pin and guide are essentially the same as those described and shown in my United States patent mentioned hereinbefore, to which reference may be had for details of construction and operation not disclosed herein. As pointed out in the aforesaid issued patent, the fore end of the lower bow member is provided with a longitudinally extending slot 100 which receives the tongue depending from the base of the incisal guide.

Referring particularly to FIGURES 10, 11 and 12, a face bow mounting post, generally designated 102, is provided with a tongue 104 at the base thereof and a screw 105 threaded into the latter. The head of the post, designated 106, is provided with a cap 110. Conjointly formed by the head 106 and cap 110 is an opening 114. On one side of the post the cap 110 is hinged to the head 106, as at 116, and upon the opposite side of the post the cap 110 is detachably secured to the head 106 by a screw 118.

Referring particularly to FIGURES 13, 14 and 15, a clutch mounting post, generally designated 120, is provided with a tongue 122 at the base thereof and a screw 124 threaded into the latter. The post 120 mounts a cross arm 126 having a portion intermediate the ends thereof grooved, as at 128, and slidably fitted to the post 120, the arm being thereby inclined as shown. A screw 130 is projected through a slot 131 in the post 120 and is threaded into the cross arm 126 for clamping the cross arm to the post. The opposite end portions of the cross arm 126 are each provided with an opening 132 and a screw 134.

Referring particularly to FIGURE 4, a conventional face bow, generally designated 136, is provided with a crossbar 138, a pair of arms 140 extending laterally from opposite end portions of the bar 138 and secured thereto by fittings 142. Each arm 140 carries an auxiliary arm 144 pivoted, as at 146. The arm 144 suitably mounts a condyle pin 148 and is spring biased, as at 152, against the lower end of a stop screw 154. Mounted upon the crossbar 138 are fittings 156 and 158. Extending upwardly from the fitting 156 is a standard 162 provided with a lateral extension 164 at the upper end thereof, and extending rearwardly from the fitting 158 is a clutch bar 166 mounting a clutch tray 168.

In the fabrication of artificial dentures, the patient is directed to close on a bite fork (not shown) mounted on the face bow 136. The condyle pins 148 and the standard 162 are then adjusted temporarily, all in known manner.

The next step is to remove the incisal pin 96 and incisal guide 98 from the articulator and to substitute for the guide 98 the face bow mounting post 102. This is accomplished by fitting the tongue 104 of the post 102 into the slot 100 formerly occupied by the tongue depending from the base of the guide 98, and by removably securing the post in position as by the screw 105. Next the face bow 136 and the bite fork mounted thereon are removed as a unit from the patient's face and mounted upon the post 102. This is accomplished by lifting the cap 110, setting the fork bar on the head 106, relowering the cap 110 and clamping the bar in position by tightening the screw 118. Thus the face bow is mounted in overlying spaced relation to the lower bow member of the articulator.

The upper bow member of the articulator may now be mounted upon the face bow. This is accomplished by turning hinge parts 34 about their longitudinal axes 180 degrees, from the position shown in FIGURE 2 to that shown in FIGURE 3, wherein the index mark 69 is shown matching the index mark 75. Then the hinge parts 34 are spaced equidistantly from the upright longitudinally extending medial plane through the upper bow member and a distance apart suitable for acceptance of the points 150 of the condyle pins 148 by the abut-

ments 90. Thus the rear end of the upper bow member is carried by the condyle pins 148. The fore end of the upper bow member is placed upon the extension 164 of the standard 162.

An upper stone model made from a suitable impression is now mounted upon the upper bow member 30 by seating the model upon the fork aforesaid, swinging the upper bow member 30 upwardly and rearwardly, applying plaster to the top of the model, turning the upper bow member 30 back to its initial position and allowing the plaster to harden.

Now a lower stone model made from a suitable impression is mounted upon the lower bow member. This is accomplished by first removing the upper section of the articulator, the face bow and face bow mounting post from the lower section of the articulator. Then the upper and lower sections of the articulator are assembled, using incisal pin 96 and guide 98 to level the upper section 30. Now the whole assembly is turned upside down. Then the lower model is related to the upper model by using a centric relation record. Now the lower section of the articulator is swung upwardly and rearwardly, plaster is applied to the lower model, the lower bow member is turned back to its initial position and the plaster is allowed to harden.

The next step in the procedure is to make clutch trays and ready the same for mounting in the patient's mouth. The incisal pin 96 and guide 98 are removed from the articulator, and the guide 98 is replaced with clutch tray mounting post 120. This is done by fitting the tongue 122 into the slot 100 and by securing the same in position as by screw 124. Now the screws 134 are loosened, the clutch bars 166 projected through openings 132, and the screws retightened. Then screw 130 is loosened, cross arm 126 moved to a suitable height and screw 130 retightened. The trays, designated 168, are now formed in known manner over the stone models and attached to the clutch bars 166. Then the models are closed on the trays, as shown in FIGURES 5 and 6, wherein the upper and lower stone models are designated respectively 172 and 174, and the plaster securing the same to the upper and lower articulator sections respectively is designated 176 and 178. The clutch trays, with the clutch bars affixed thereto, are now transferred to the patient's mouth, and the trays are cemented in place.

The next step is to locate the center of rotation by using the face bow and to mark the face in known manner. The face bow is then transferred from the lower to the upper clutch bar and a final adjustment is made to all three reference marks on the patient's face. The upper clutch bar, upper tray and face bow are now separated as a unit from the patient's teeth, and the lower clutch bar and lower tray are separated as a unit from the patient's teeth.

The next step is to remount the upper section of the articulator upon the face bow. Referring particularly to FIGURE 4, this is accomplished by first mounting the face bow post 102 upon the lower bow member of the articulator and clamping the face bow to the post 102 in the manner described hereinbefore. Then the hinge parts 34 of the upper articulator section are turned about their axes so that abutments 90 face outwardly in opposite directions. The hinge parts are positioned on opposite sides of the upright longitudinally extending medial plane of the upper bow member and at an effective distance apart equal to the clear distance between the opposed points 150 of the condyle pins 148. The condyle pins 148 are forced apart slightly so that the points 150 thereof may pass over the rims of the abutments 90, and then they are released, whereupon the points 150 spring back toward one another and enter respectively the conical depressions 94. The fore end portion of the upper bow member 30 is seated upon the extension 164 of the standard 162.

Now the upper tray 168 is attached to the upper

section of the articulator. The latter is swung upwardly and rearwardly and stone, designated 180, is applied to the tray, and then the bow member is turned back to its initial position and the stone allowed to harden.

Now the lower tray 168 is attached to the lower section of the articulator. This is accomplished by first removing the upper section of the articulator, the face bow 136 and the face bow mounting post 102 from the lower section of the articulator. Then, referring particularly to FIGURES 7, 8 and 9, the incisal pin 96 and guide 98 are remounted respectively upon the upper and lower sections of the articulator, and the upper section 30 is remounted upon the lower section 10. Now the instrument is turned upside down, as shown in FIGURE 7, and the lower tray 168 is set in correct relation to the upper tray 168 by using a proper stone check. Then the lower bow member 10 is swung upwardly and to the rear, stone, designated 182, is applied to the lower tray, the lower bow member 10 is returned to its initial position and the stone is allowed to harden, as shown in FIGURES 8 and 9.

It should be noted that there is no need for the cumbersome auxiliary mounting table mentioned hereinbefore. Instead, the lower bow member 10 fitted with the face bow mounting post 102 is conveniently used. In addition, the points of the condyle pins positively interengage with abutments 90, in consequence of which the weight of the stone does not cause misalignment of the hinge axis extending through the abutments 90 relative to the axis extending between the opposed points of the condyle pins. The face bow and the upper bow member of the articulator do not move relative to one another. If they move at all, they move as a unit.

Referring particularly to FIGURES 7, 8 and 9, the clutch bars are positively located by the clutch tray mounting post 120 so that they cannot possibly interfere with the incisal pin 96 or guide 98. No reliance is placed upon the operator's good judgment to properly orient the clutch bars 166 relative to the incisal pin 96. The abutments 90 are adapted for operatively coacting with a face bow having condyle pins of the pointed type or with condyle pins of the type provided with depressions or sockets in the opposed ends thereof. Finally, the incisal guide 98, face bow mounting post 102 and clutch bar mounting post 120 are interchangeably mounted upon the lower bow member 30.

Referring particularly to FIGURES 16 to 20, a modified form of the face bow mounting post, generally designated 190, which may be used to advantage in lieu of face bow mounting post 102, comprises lower and head sections, respectively designated 192 and 194, square in transverse section. The lower section 192 is split fore and aft, as at 196, to form laterally spaced furcations 198. The upper section 194 is undercut to form a pair of shoulders 200 respectively on opposite sides of a tongue 202 extending downwardly between the furcations 198. Extending freely through one of the furcations 198 and through the tongue 202 and threaded into the other furcation 198 is a screw 204 having a knurled head 206. When the screw 204 is tightened the furcations 198 are forced into engagement with the tongue 202 and the head section 194 is adjustably secured in position relative to the lower section 192. The terminal portions of the furcations 198 are sloped, as at 208, to clear the shoulders 200 of the head section 194 when the latter is tilted fore or aft. The head section 194 is provided with an opening 210 extending fore and aft therethrough. A screw 212 having a knurled head 214 is threaded into the head section 194 and is adapted to enter the opening 210 from one side thereof. The lower end portion of the section 192 is undercut to provide a shoulder 216 and a cylindrical element 218 depending therefrom. The diameter of the element 218 is slightly less than the width of the slot 100 formed in the fore end portion of the lower bow member. Threaded into the element 218 is a screw 220 provided with a head 222.

Referring particularly to FIGURES 19 and 20, the face bow mounting post 190 is shown mounted upon the fore end of the lower bow member. The element 218 is slidably fitted into the slot 100 and the shoulder 216 is seated upon the upper surface of the lower bow member. The post is adjustably affixed in position by the screw 220. The clutch bar 166 is slidably projected through the opening 210 and secured by the screw 212. It will be observed that the clutch tray 168, clutch bar 166 and face bow 136 may be tilted as a unit vertically fore and aft by loosening the screw 204, tilting the head section 194 to the desired degree relative to the lower bow member and then retightening the screw 204. In addition, the clutch tray 168, clutch bar 166 and face bow 136 may be swung laterally to the right or to the left as a unit by loosening the screw 220, turning the post about its longitudinal axis to the desired degree and then retightening the screw 220. Furthermore, the clutch tray 168, clutch bar 166 and face bow 136 may be tilted laterally as a unit vertically by loosening the screw 212, turning the bar 166 about its axis to the desired degree and then retightening the screw 212. Thus universal type adjustment of the face bow relative to the lower bow member is achieved.

It will be understood, of course, that the present invention, as shown and described, is susceptible to various changes and modifications which may be made without any departure from the general principles of the invention. Accordingly, it is intended to claim the present invention broadly, as well as specifically, as indicated in the appended claims.

What is claimed is:

1. In apparatus for use in dental prosthesis, the lower bow member of a dental articulator, the upper bow member of a dental articulator, and means mounting said members in mutually overlying relation including laterally spaced corresponding hinge parts mounted at the rear of said upper bow member and having undersurfaces simulating the condyle paths in the natural skull and abutments

facing away from one another along a hinge axis common to said hinge parts, an upright post mounted upon the fore end of said lower bow member, a clamp carried by said post, and a dental face bow affixed to said post by means of said clamp and extending rearwardly therefrom, said face bow including opposed condyle pins, said upper bow member being mounted upon said face bow with the opposed condyle pins of said face bow received respectively by said abutments, the ends of said condyle pins being thereby positioned in registry with said hinge axis and with the fore part of said face bow underlying the fore end of said upper bow member, said upper bow member being thereby mounted for swinging movement upwardly and rearwardly about said hinge axis.

2. The combination comprising a dental articular including a lower bow member, an upper bow member, means for mounting said members in mutually overlying relation, a post detachably affixed to, and extending upwardly from, the fore end portion of said lower member, a vertically adjustable cross arm carried by said post, a pair of bars respectively at opposite ends of said cross arm extending rearwardly from said post at different levels, vertically spaced clamp means carried by said cross arm and receiving and holding said pair of bars, and clutch trays carried by said bars.
